CAMOUFLAGE AND METHOD OF MAKING

St. Clair M. Hale, Detroit, Mich., assignor to
Parker-Wolverine Company, Detroit, Mich., a
corporation

Application June 17, 1943, Serial No. 491,156

6 Claims. (Cl. 117—37)

The invention relates to the art of camouflaging and it has particular relation to an improved type of camouflage and process of making the same.

Particularly in wartime, it is important that certain locations be covered by overhead camouflage for the purpose of concealing objects or for the purpose of so disguising the terrain as to confuse or disguise aerial observation. At the present time, much observation is effected by photography and subsequent to the taking of photographs, the pictures are studied. In view of this practice, it is exceedingly important that the camouflage have such relation to light reflectivity as to show on the photographic plate something which confuses the enemy or gives him a clearly erroneous view.

One object of the present invention is to provide an improved article for camouflaging purposes which will have such light reflectivity characteristics as to more or less negative results obtained photographically by enemy aerial observers.

Another object of the invention is to provide an article of this character which may be manufactured very inexpensively, which is practically weatherproof, and which may be installed or applied rapidly.

Another object of the invention is to provide an improved method of making an article for camouflaging purposes out of wire netting, or fencing, wherein camouflaging material is applied to the wires in an efficient and rapid manner.

Other objects of the invention will become apparent from the following specification, the drawings relating thereto, and from the claims hereinafter set forth.

For a better understanding of the invention, reference may be had to the accompanying drawings, wherein:

Figure 1 is a more or less diagrammatic view illustrating apparatus which may be employed in the manufacture of camouflaging articles according to one form of the invention;

Figure 2 is a fragmentary view illustrating an article for camouflaging purposes as constructed according to one form of the invention.

Referring to Figure 2, the camouflaging article comprises a wire netting or fencing indicated at 10 and while the netting shown may be on the order of so-called chicken wire or fencing, it will be understood that other forms of netting or fencing may be employed as long as it is of open-

mesh character. The camouflaging material applied to this netting comprises a fibrous and paint mixture 11 which, when solidified, becomes firmly attached to the wires. The fibrous material may comprise asbestos fiber, short staple cotton fiber, or other similar fiber, and in the structure shown in Figure 2, the fibers mainly extend in parallel relation. Also, the fibers principally may be looped or folded about the cross wires so that the end portions of the fibers may extend transversely to the mesh openings with the fibers mainly extending in the same direction from the wires to which they are attached. By having the fibers impregnated with paint and applying the mixture in fluid form, solidification effects firm adhesion of the fibers together and to the netting so that as a final result the fibrous material partially or even completely closes the mesh openings and is fairly rigid in character.

20 Preferably, where a paint of green color is used, the paint will contain a pigment having substantially the same index of infra-red light reflectivity as is found in chlorophyll. By having this light reflection characteristic, photographs 25 of any territory covered by camouflaging netting of the type described will show on the photographic plate in about the same manner as green landscaping, green fields, woods or the like.

In manufacturing the article, a container 13 30 may be provided as seen in Figure 1 and the paint and fibers are deposited in this container and thoroughly mixed by any suitable means such as an agitator 14. The quantity of fibers in the paint may vary, but the mixture will be sufficiently thick so as to obtain the desired depositing of fibers on the wire. A coil of wire netting or fencing is indicated at 15 and this netting is conducted over suitable rollers 16, 17, and 18 located in the tank. At the discharge side of 35 the tank, the netting passes between a pair of squeeze rollers 20 and 21 constructed of rubber or other suitable material which squeeze out surplus paint and at the same time press the fibers together and into the plane of the wire.

40 During movement of the netting through the mixture, the latter is maintained in an agitated condition and the cross wires pick up or catch paint impregnated fibers. Altogether, as the wire drags through the mixture, substantial quantities of paint laden fibers catch on the wire and depend therefrom, and as the wire moves between the squeeze rollers 20 and 21, the fibers are pressed 45 into the mesh openings mainly at the lag side of the wires from which they are suspended. The 50 55

squeezing action is sufficient to bring the fibers into close, adhering relation and after they pass between the rollers, the attachment of fibers to one another and to the various wires by means of the paint holds them substantially in the plane of the netting. After passing between the squeeze rollers, the netting passes between drying apparatus such as the infra-red lights 22 and 23 where the paint is substantially dried. The product then comprises a dried mass of paint impregnated fibers disposed transversely to the wires and held together by the wires and by the paint binder.

Although only one form of the invention has been described and illustrated in detail, it will be apparent to those skilled in the art that various modifications may be made without departing from the scope of the appended claims.

What is claimed is:

1. The process of manufacturing camouflage which comprises mixing liquid paint and loose fibrous material, passing an open-mesh netting through the mixture so that the strands of the netting become coated with paint and collect substantial quantities of the paint covered fibers, and then drying the netting.

2. The process of manufacturing camouflage which comprises applying paint and loose fibrous material to an open-mesh netting so that paint-impregnated fibers collect on the strands of the netting, passing the netting screen between squeeze rollers so as to remove surplus paint and to press the fibers and netting into substantially the same plane, and then drying the netting.

3. The process of manufacturing camouflage

which comprises mixing paint and loose fibrous material in a container, passing netting through the mixture so that the strands of the netting become coated with paint and so that paint-impregnated fibers become caught or suspended on the cross strands as the latter advance through the mixture, then passing the netting between squeezing elements to remove surplus paint and to move the suspended fibers into the mesh openings and substantially into the plane of the netting, and then drying the netting with the fibers in such position.

4. The process of manufacturing camouflage which comprises mixing paint and loose fibrous materials, passing open-mesh woven wire netting through the mixture so that paint-impregnated fibers collect or become suspended on the wires, then passing the netting between squeezing elements to remove surplus paint and to substantially dispose the fibers in the plane of the netting, and then drying the netting.

5. A camouflage article comprising an open-mesh netting having paint-impregnated fibers looped around strands of the netting with the fibers generally extending in the same direction transversely to the mesh openings and in substantially the plane of the netting, the paint as solidified serving to hold the fibers in position.

6. A camouflaging article comprising an open-mesh netting having fibers disposed transversely to the mesh opening and lying substantially in the plane of the netting, and a solidified liquid material coating said fibers and serving to hold them in position on the netting.
